COMPOUND PROPULSION SYSTEM

Theodore N. Edelbaum, Windsor, Conn., and Edward A. Pinsley, Cambridge, Mass., assignors to United Aircraft Corporation, East Hartford, Conn., a corporation of Delaware

Filed Feb. 6, 1961, Ser. No. 87,394

14 Claims. (Cl. 60—35.6)

This invention relates to a compound propulsion system and more particularly to a propulsion device having inter-related propulsion units with one of the units being a high-thrust, short-duration device and the other of the units being a low-thrust, high-specific impulse, long-duration device.

In certain space missions it is desirable to obtain short-duration impulsive thrust for rapid maneuvering. It is also desirable to have relatively long-duration low thrust available for efficient long-range operation. Electric propulsion systems serve the latter purpose but are not adequate for maneuvering, since the weight of the required electrical generating system would be prohibitive.

It is, therefore, a primary object of this invention to combine an electrical propulsion device with a chemical rocket, with the chemical rocket being utilized for short-duration, high-thrust maneuvering purposes.

It is a further object of this invention to provide a combined chemical and electrical propulsion device with one or more of the fuels for the chemical rocket being utilized jointly in both propulsion devices.

These and other objects of this invention will become readily apparent from the following detailed description of the drawing which illustrates a schematic arrangement of a type of compound propulsion system of this invention.

Referring to the FIGURE, a fuel storage tank containing, for example, lithium, is indicated at 10. The lithium is used as a common fuel in both the rocket propulsion unit 12 and the electric propulsion unit 14. The electrical propulsion unit 14 eventually obtains its power through a suitable generator (referred to hereinafter at 54) which generator in turn receives power from a combined primary power circuit 16 and a secondary power circuit 18. The propulsion unit 14 is illustrated by example as a bombardment ion engine but may readily take the form of an arc jet (which may accelerate hydrogen received from the rocket source), a magneto-hydrodynamic accelerator or other ion engine. The lithium from the storage tank 10 is pumped by one or more pumping units 20 and 22 into the primary circuit 16 through a suitable nuclear reactor 24. The nuclear reactor, which may be of any well-known type, adds heat to the liquid lithium and discharges the heated lithium from a line 26. Suitable valves 28 and 30 control the flow of lithium into a heat exchanger coil 34 so that the lithium, in fact, circulates from the nuclear reactor 24 to the heat exchanger coil 34 and then back to the reactor for added heating. The heat exchanger receives flow of a suitable working liquid (for example, a liquid metal) from a pump 40 and an inlet line 42. This liquid flows in the secondary circuit 18. The liquid picks up heat in the heat exchanger and discharges the heated working fluid into a line 44 and a suitable turbine 46. Exhaust from the turbine 46 passes to a suitable radiator 48 for the release of excess heat energy. The exhaust from the radiator passes through a line 50 and back to the pump 40.

It should be noted that the working liquid is vaporized in the heat exchanger, and after passing through the turbine 46 is again condensed in the radiator 48. The turbine 46 drives an electric generator 54 which in turn provides the electrical energy for the electrical propulsion unit 14. The propulsion particles, which are accelerated

2

out of the exhaust of the propulsion unit 14 by electrical means, comprise lithium ions which are supplied via the line 60. A valve 62 leading from the primary circuit 16 expands a very minute portion of lithium and directs it to the electrical propulsion unit 14, which for example, may be a bombardment ion engine. The lithium is ionized in the ion engine 14 and the lithium ions are accelerated in the ion engine 14, thus providing specific impulses in the range from 2,000 to 20,000 seconds. The major portion of the lithium remains in the primary circuit.

When short-duration impulsive thrust is desired, a relatively large amount of lithium can be directed from the primary circuit 16 through the valve 70 leading to the line 72. The line 72 leads to the combustion chamber of the chemical rocket 12. The chemical rocket when in operation is also fed fuel and oxidizer (for example, hydrogen and fluorine) from respective containers or tanks 74 and 76. A suitable pump 78 and valve 80 are provided for the hydrogen which is fed through the line 82, while a pump 84 and valve 86 conduct the flow of fluorine to the line 85.

Each of the lines 72, 82, and 84 conducts one of the three propellants which comprise the combustion products for the rocket 12.

Thus, for very high thrust of short duration, the tri-propellant rocket gives a very high, specific impulse. If further energy is desired, it may be feasible to connect the hydrogen and fluorine tanks in any suitable manner to the nuclear reactor, as schematically illustrated by the dotted lines 90 and 92. Thus, the chemical propellants would all be pre-heated before being introduced into the rocket combustion chamber.

As a result of this invention, both high-thrust and low-thrust operation is readily achieved. The fuel inventory for ferrying operations is substantially reduced. In addition, less cryogenic tankage is required than for an ordinary hydrogen-fluorine propellant system. Of further importance is the fact that a portion of the chemical rocket propellant, formerly charged off to payload, may now be used as electrical propulsion fuel. Furthermore, the continual replenishment of lithium in the closed-loop primary circuit will alleviate the problem of poisoning of the reactor coolant. In addition, lithium has a low-neutron absorptive quality which makes it acceptable to nuclear heating without contamination. Finally, very high specific impulse is achieved in the chemical rocket, particularly if the nuclear reactor temperatures are such that the lithium is introduced in the vapor state.

Although one embodiment of this invention has been illustrated and described herein, it will be apparent that various changes may be made in the construction and arrangement of the various parts without departing from the scope of the novel concept.

What it is desired by Letters Patent is:

- 55 1. A compound propulsion unit including a rocket, means for supplying a plurality of propulsion ingredients to said rocket, an electrical propulsion device and means for conducting one of said ingredients to said electrical propulsion device for acceleration therein.
- 60 2. A compound propulsion unit including a rocket, means for supplying a plurality of propulsion ingredients to said rocket, an electrical propulsion device including means for accelerating propellant therein, and means for conducting one of said ingredients to said electrical propulsion device for supplying the propellant to be accelerated.
- 65 3. A compound propulsion unit including a rocket, a plurality of propulsion ingredients including a source of lithium, means for supplying said ingredients to said rocket, an electrical propulsion device, and means for conducting lithium from said source to said electrical propulsion device for acceleration therein.

4. A compound propulsion unit comprising a rocket device and an electrical propulsion device, and means for supplying at least one ingredient as a common propulsive ingredient to both said devices.

5. A compound propulsion device including a rocket, sources of three propulsive ingredients, means for conducting said ingredients to said rocket for reaction therein, a nuclear heat source, means for converting heat energy from said source into electrical energy, an electrical propulsion device receiving electrical energy from said converting means, and means conducting a relatively small portion of one of said ingredients to said electrical propulsion device for acceleration therein.

6. A compound propulsion device including a rocket, sources of a plurality of propulsive ingredients including an element which is readily ionized, means for conducting said ingredients to said rocket for reaction therein, a heat source, means for converting heat energy from said source into electrical energy, an ion propulsion device receiving electrical energy from said converting means, and means conducting a relatively small portion of said element to said ion propulsion device for ionization and subsequent acceleration.

7. A compound propulsion device including a rocket, a plurality of sources of different propulsive ingredients, means for conducting said ingredients to said rocket for reaction therein, a heat source, means for converting heat energy from said source into electrical energy, an electrical propulsion device receiving electrical energy from said converting means, and means conducting a relatively small portion of one of said ingredients to said propulsion device for use as a propellant.

8. A compound propulsion device including a rocket, a plurality of sources of different propulsive ingredients, means for conducting selective amounts of said ingredients to said rocket for reaction therein, a heat source, means for converting heat energy from said source into electrical energy, an electrical propulsion device receiving electrical energy from said converting means, and means conducting a relatively small portion of one of said ingredients to said electrical propulsion device for acceleration therein.

9. A compound propulsion system comprising a first cycle, said cycle having a first working fluid, a first path for circulating said first working fluid, a source of heat for adding energy to said working fluid, a heat exchange unit receiving said working fluid, a second cycle including a second working fluid, means connecting said second cycle to said heat exchanger means to extract energy therefrom, means in said second cycle for converting the energy from said second working fluid into electrical energy, an electrical propulsion device receiving electrical energy from said converting means, means for conducting working fluid from said first cycle to said electrical propulsion device, and a rocket receiving a portion of said first working fluid for use as thrust producing material.

10. A compound propulsion system comprising a first cycle, said cycle having a first working fluid which is readily ionized, a first path for circulating said first working fluid, a source of heat for adding energy to said working fluid, a heat exchange unit receiving said working fluid, a second cycle including a second working fluid, means connecting said second cycle to said heat exchanger means to extract energy therefrom, means in said second cycle for converting the energy from said second working fluid into electrical energy, an ion propulsion device receiving electrical energy from said converting means, means for conducting working fluid from said first cycle to said ion propulsion device for supplying the ions to be

4
accelerated, a rocket power plant, a plurality of sources of propulsive ingredients for said rocket and means for conducting at least a portion of said first working fluid to said rocket for reaction with said ingredients.

5 11. A compound propulsion system including a rocket, sources of three ingredients, means for conducting said ingredients for reaction in said rocket, a first cycle receiving flow of one of said ingredients, a source heat in said first cycle for heating said one ingredient, means for extracting heat energy from said one ingredient, a second cycle including a working fluid receiving energy from said extracting means, means for converting energy in said fluid into electrical energy, a propulsion device receiving electrical energy from said converting means, and means conducting a portion of said one ingredient to said propulsion device to provide a propellant therefor.

10 12. A compound propulsion system including a rocket, sources of three ingredients, means for conducting said ingredients for reaction in said rocket, a first cycle receiving flow of one of said ingredients, a source of nuclear heat in said first cycle for heating said one ingredient, means for extracting heat energy from said one ingredient, a second closed cycle including a working fluid receiving energy from said extracting means, means for converting energy in said fluid into electrical energy, an ion propulsion device receiving electrical energy from said converting means, and means conducting a portion of said one ingredient to said propulsion device for acceleration therein.

15 13. A compound propulsion system including a rocket, sources of propulsion ingredients comprising hydrogen, fluorine and lithium, means for conducting said ingredients for reaction in said rocket, a first cycle receiving flow of lithium from one of said sources, a source of nuclear heat in said first cycle for heating said lithium, means for extracting heat energy from said heated lithium, a second cycle including a working fluid receiving energy from said extracting means, means for converting energy in said fluid into electrical energy, a bombardment ion propulsion device receiving electrical energy from said converting means, and means conducting a portion of said lithium to said propulsion device for acceleration therein.

20 14. A compound propulsion system including a rocket, sources of three ingredients, means for conducting said ingredients for reaction in said rocket, a first cycle receiving flow of one of said ingredients, a source heat in said first cycle for heating said one ingredient, means for extracting heat energy from said one ingredient, a second closed cycle including a working fluid receiving energy from said extracting means, means for converting energy in said fluid into electrical energy, an electrical propulsion device receiving electrical energy from said converting means, and means conducting a portion of said one ingredient to said propulsion device for providing a thrust-producing material for said device.
